(57) CLAIM

The ornamental design for a shoe, as shown and described.

DESCRIPTION

FIG. 1 is a front perspective view of an upper portion of a shoe showing my new design.

FIG. 2 is a rear perspective view thereof.

FIG. 3 is a side view thereof.

FIG. 4 is a front perspective view of an outsole portion of a shoe showing my new design.

FIG. 5 is a rear perspective view thereof; and,

FIG. 6 is a plan view thereof.

The broken lines immediately adjacent to the shaded areas represent unclaimed boundaries of the design. The uneven broken line showing of the remainder of the shoe is for illustrative purposes only and forms no part of the claimed design.
